UNITED STATES PATENT OFFICE.

HUBERT C. VERHEY, OF ST. LOUIS, MISSOURI, ASSIGNOR TO BUSCH-SULZER BROS. & DIESEL ENGINE COMPANY, OF ST. LOUIS, MISSOURI, A CORPORATION OF MISSOURI.

COMBUSTION-ENGINE PUMP MECHANISM.

1,269,882.

Specification of Letters Patent. Patented June 18, 1918.

Application filed February 10, 1917. Serial No. 147,782.

To all whom it may concern:

Be it known that I, HUBERT C. VERHEY, a citizen of Holland, residing in St. Louis, Missouri, have invented the following-described Improvements in Combustion-Engine Pump Mechanism.

The invention relates to the oil and water pumping apparatus of internal combustion or Diesel engines and particularly those used for the propulsion of vessels, the water constituting the cooling medium for the cylinder jackets and the oil for the pistons or for lubrication if desired, although the nature of the uses to which the pumped media are put is not of consequence. The principle of the present invention accommodates a liberal pumping capacity and a maximum facility for control and inspection to the severe limitations imposed by the marine service, in respect to balance and space occupied, and the invention provides a pumping organization especially suited for submarine engines, capable of symmetrical disposition on the main engine structure, at the end of the crank shaft, where its weight is not only balanced with respect to said shaft but where all of its parts are accessible for attention and repair and whereby the various connections for the water and oil are all conveniently located and controlled and whereby numerous important, though incidental advantages are secured, all of which will be described or made fully apparent to those skilled in this art from the detailed description which follows. In the illustrative drawings forming part hereof:

Figure 1 is a partial vertical section and partial elevation of a preferred embodiment of the invention, as viewed from the end of the engine;

Fig. 2 is vertical section, with parts in elevation, of the same apparatus taken at right angles to Fig. 1;

Fig. 3 a reverse elevation with parts broken out in vertical section;

Fig. 4 an elevation of the main parts with the various connections omitted for clearness; and

Fig. 5 is a horizontal section on line V—V of Fig. 1.

The drawings show the terminal portion

of the engine bed plate 1 on which the engine crank shaft 2 is journaled and Fig. 2 illustrates also part of the engine superstructure, the part shown being a portion of the compressor apparatus 3 of a multi-cylinder Diesel engine, the said compressor being disposed at the forward end of the engine and direct driven from the terminal crank of the main crank shaft. The water jacketed wall 4 of the air compressor cylinder and the adjacent structure and the end flanges of the bed plate 1, all constitute the support for the pumping organization about to be explained, and the intermediate space is closed in by said apparatus which thus constitutes the end closure to the main crank chamber of the engine.

The pumping organization is duplex and also symmetrical with reference to the vertical plane of the crank shaft, the water pumping system being at the top and the oil near the bottom, and the pumping units of each system are divided equally with respect to said vertical plane, the water units being spaced one on each side at the top and the oil units one at each side at the bottom with the several cylinders on each side preferably, though not necessarily, disposed in vertical alignment with each other. This symmetrical arrangement may quite obviously be varied according to circumstances but is preferred for reasons of compactness. The drive for all the units is disposed centrally of the entire group and between the lower or oil pump cylinders. The entire organization is thus balanced with respect to the main axis of the engine so that no part of the described apparatus would tend to list a single screw vessel. Each water pumping unit is a separate casting and a reverse duplicate of its mate and is separately bolted to the wall of the engine superstructure as indicated in Fig. 2. Each said unit includes a pump cylinder 5 and a valve chest 6 and the valve chest in each case is disposed on the outer side of the pump cylinder 5, that is to say on the outer side of the unit structure with reference to the engine crank shaft, this arrangement being for accessibility as presently described and particularly when additional apparatus obstructs the forward end of the engine. The

valve chests are supplied with water through the water main 7, valves 8 and 8^a (Fig. 5) and the suction pipes 9 and 9^a, the latter being castings bolted to the lower faces of 5 the two valve chests and lying generally in rear of the plunger rods as shown in Fig. 5. Each valve chest accommodates two intake valves 10 and two outlet valves 11, the former being contained in separate compartments 12 in ported communication with the pumping cylinder 5 and the outlet valves are contained in the single outlet chamber 13 which leads across the top of cylinder 5 inwardly or toward the center of the organization 15 where the water pumped by each unit may escape through the branch 14 of a three-way cock 15. This cock controls the entrance to the air dome 16, which air dome is common to both pump units and is carried jointly by them. The said dome includes an air trap inside of it and the water therefrom flows to the water jackets of the air compressor 3 and working cylinders or elsewhere, as needed, through a separate 20 delivery pipe 18. The two inlet chambers 12 in each valve chest and the outlet chamber 13 therefor may all be opened for inspection by unbolting the single cover plate 19 which forms the outside wall of the chest 25 30 and the inlet and outlet valves may be removed and inserted through such openings. Each of the pump valves is of the self contained type not requiring detailed description, and includes a removable valve seat 35 ring 20 (Fig. 3) containing the valve port openings and a valve disk 21 to close such openings, the said disk being guided on the central stem part of the seat ring which terminates in its upper end in a thrust 40 screw 22 or in a bearing for a thrust screw, as the case may be. The said rings are fitted to apertures in the horizontal partitions of the valve chest, in vertical alinement and the thrust screw of the lower (inlet) valve 45 thrusts against the center of the valve seat member of the upper (outlet) valve while the thrust screw of the latter finds its abutment against the under side of the top plate 23, which is securely bolted to the upper 50 surface of the valve chest. With this arrangement, and all the valves being similarly assembled, it will be observed first, that the removal of the single cover plate 19 from the side of the valve chest exposes 55 all the valves therein so that no time is lost, as heretofore, in seeking a defective valve and second, that any or all of the valves may be removed and substituted by others in very short order and by simply slackening off the pressure of its thrust screw sufficiently to permit removal of its seat ring from the aperture in the chest partition. This may be accomplished even while the engine and pumping mechanism is running 60

because either unit may be disconnected 65 and isolated from the circulating system by an appropriate shutting off of the valves 8 or 8^a and the three-way cock 15 and also because the time required for substitution of valves in this manner is so brief that the remaining unit, still working, is quite adequate to maintain the cooling effect during so momentary a shut-down of the incapacitated unit. It will of course be apparent that various types of removable valve structures and various methods of assembling them in the valve chest can be used in a structure of the kind above described and having the functions and advantages just alluded to. 70 75 80

The interior of the water pump cylinder 5, in each unit, is accessible for inspection or for the removal of its plunger by the removal of its head plate 24 which is normally clamped against the end of the cylinder by the screw strut 25, which latter thrusts against the bolted cover plate 26 and centrally intercepts the outlet channel 13 above referred to, which said channel crosses over the upper end of the pumping cylinder 90 in order to effect a free passage to the valve fitting 15. 95

The connection of the two water units by the fitting of the three-way valve 15 serves to unite and brace the said units on the engine structure. The said units however are further braced and also directly supported by the intervening structure 27, which is securely bolted to the flanges 28 projecting inwardly from the proximate side of the two units just below the outlet fitting 15. The structure 27 is formed of longitudinal parts or halves which, when bolted together, (Fig. 4) form a tubular structure adapted to constitute a central guiding slideway for the tail rod member 29 of the cross head 30 through which cross head reciprocating motion is imparted to the several pumping plungers of the organization. The said cross head and tail rod are shown in the present case as a one-piece forging centrally connected by a connecting rod 31 to the crank pin of a spur gear 32 driven from the overhanging crank shaft pinion 33 and journaled on a stud shaft 34 projecting from the engine bed just below the terminal crank shaft bearing thereof. This disposition of the pump driving gear 32, centrally below the crank shaft axis, not only provides a desired speed reduction for the pumping mechanism but also permits the location of the pump cylinders generally at the lowest point on the engine structure and with a minimum lateral thrust on the cross head. The gears 32 and 33 and the connecting rod 31 are housed in a casting 35 of plate form bolted to the engine bed at 36 and 37, the said casting being formed or pro- 100 105 110 115 120 125

vided with a forwardly projecting bonnet part which immediately houses the parts referred to. This projecting bonnet member 35 is shown more clearly in Fig. 2 and, being rigidly mounted on the engine structure, it forms the base for the post members 38 and 39 which extend upwardly therefrom to the slideway or guide structure 27 above referred to. The said structure is provided 10 with lateral lugs on each side of the tail rod for connection with these post members and the latter are constituted of thrust sleeves and tie bolts as clearly shown in Fig. 2. Together with the guideway structure 27 these post members 38 and 39 serve to tie 15 the water cylinders 5 securely to the housing and journal bearing of the crank gear 32 and thereby relieve the bolt flanges above referred to of undue strain. The posts 38 and 39 are preferably disposed in the vertical plane of the engine crank shaft, one on 20 each side of the connecting rod, although their tying and bracing functions may obviously be performed by different structures 25 connected in different relations to the said rod. The forward end of the bonnet 35 is covered by a removable plate 40 to confine the lubricating oil in the bonnet and at the same time to permit access to the gears when 30 necessary. Such cover is removable without disturbing the oil pump mechanism presently described. The opening in the upper wall of the bonnet 35 which accommodates the connecting rod 31 is small in area because of its proximity to the cross head, but 35 is protected by a guard plate as indicated. The tail rod 29 is hollow for the sake of lightness and also to provide a passage for oil from the drip oiler 41 (Fig. 2) which 40 lubricates not only the tail rod in the slideway 27 but also the connecting rod pivots through the oil ducts in the bottom of the tail rod. The opposite ends of the cross head structure 30 are connected to the plunger rods 42 of the two water pumps so that 45 these two pumps are operated in unison and the leakage past the glands 43 is caught in a cup 44 fixed upon and around the plunger rod and drained away to the bilge by the pipe 45. Gland leakage is also minimized by a drainage outlet 46 from the interior of the gland itself, a very desirable adjunct in those forms of this invention in which the 50 water pumps are double-acting. The drip from both pipes 46 and 45 is at one side of the bonnet 35 and finds its way to the bilge without possibility of contaminating the oil. Both of the water pumping units are provided with safety valves 47 and pipe connections delivering back to the suction line and also with by-pass connections 48 between the outlet and suction sides.

The two oil pump units, being also reverse duplicates of each other are secured to the

end plate casting 35 on each side of the bonnet by means of their attachment brackets 50 (Fig. 3) and their pumping plungers 51 are secured to the cross head arm in alignment with the plunger rods 42. The inlet to each oil pump is through a pipe 52 at the lower end of the valve chest, 53 being the inlet valve and 54 the outlet which leads directly to an air dome 55 (individual to each oil pump unit) and thence to the delivery pipe by way of the valves 56. The valve chests of each pump are disposed on the outside of the pump cylinder as in the case of the water pump and are therefore easily accessible. The pipe connections thereto are equipped with suction inlet 80 valves 57 whereby either pump may be disconnected and isolated from the circulating system to which they are both normally connected in multiple relation. The intake valve 53, is removable by unbolting the cover plate 58 immediately above it and the outlet valve is removable by unbolting the air dome 55. Relief valves 59 and pipe connections are provided between the oil delivery pipe and the oil suction passage and other usual appurtenances to the oil pump will be understood without description. A casing 60, partly illustrated in Fig. 1, serves to inclose the cross head structure and is fastened to the bonnet casting 35.

Claims:

1. In an internal combustion engine marine power plant, the combination with the terminal part of the engine bed and superstructure, of a pumping organization secured to said terminal part and comprising divided pumping units disposed on opposite sides respectively of the vertical plane of the crank shaft, and an engine driven cross head member centrally disposed with respect to said units and connected to operate the plungers thereof.

2. In an internal combustion engine marine power plant, the combination with the terminal part of the engine bed and superstructure, of a pumping organization secured to such part overhanging the end of the engine crank shaft, and comprising water and oil pumping apparatus divided into units and respectively disposed on opposite sides of the vertical plane of the engine crank shaft, a cross head operatively connected to all said units and a speed reduction gearing between said cross head and crank shaft.

3. In an internal combustion engine marine power plant, the combination with the terminal part of the engine bed and superstructure, of pumping apparatus comprising a group of pumping units respectively disposed on opposite sides of the plane of said crank shaft, a cross head operatively connected to all said units and driving gearing for said cross head comprising a crank-

gear disposed below and driven by the engine crank shaft and a connecting rod connecting said gear and cross head.

4. In an internal combustion engine marine power plant, the combination with the terminal portion of the engine bed and superstructure, of duplicate pumping units secured to the upper part of said terminal portion on opposite sides of the vertical plane of the engine, duplicate pumping units secured to the lower part of said terminal portion, respectively on opposite sides of said plane, and crank-gearing between said lower pumping units centrally connected to the pumping plungers of all said units.

5. In an internal combustion engine marine power plant, the combination with the terminal portion of the engine bed and superstructure, of a crank shaft pinion overhanging the engine bed, a crank-gear driven thereby, a horizontal cross head operated by said gear, pumping units disposed above and below said cross head on both sides of the central plane of the engine, the plunger rods of said units being connected to said cross head.

6. In an internal combustion engine marine power plant, the combination with the terminal portion of the engine bed and superstructure, of a plurality of pumping units divided on both sides of the central plane of the engine, a bracing structure between units on opposite sides of said plane and a cross head disposed between the said units and guided by the said bracing structure.

7. In an internal combustion engine marine power plant, the combination of two lower pumping units divided on opposite sides of the central plane of the engine, a plunger-operating cross head centrally disposed with reference to said upper and lower units, and a crank-shaft-driven connecting-rod disposed between the two lower units.

8. In an internal combustion engine marine power plant, the combination of two upper and two lower pumping units divided on opposite sides of the engine, a cross head centrally disposed with reference to said units, a crank-shaft-driven connecting-rod disposed between the two lower units and a tail rod for the said cross head disposed between the said upper units.

55 9. In an internal combustion engine marine power plant, the combination of upper and lower pumping units divided on opposite sides of the central plane of the engine, a cross head centrally disposed with reference to said units, a driving connecting-rod disposed between the lower units, a tail rod for said cross head disposed between the upper units, and a two-part slideway for said tail rod bolted to said upper units.

10. In an internal combustion engine marine power plant, the combination of two upper and two lower pumping units all disposed in the same transverse plane of the engine and divided on opposite sides of the central plane thereof, a cross head extending horizontally between the upper and lower units and connected to the pumping plungers thereof, and crank operated driving gearing for said cross head disposed in the same transverse plane and between said lower units.

11. In an internal combustion engine marine power plant, the combination with the terminal portion of the engine bed and superstructure, of a plate casting closing the engine crank case and provided with a forwardly projecting bonnet, a crank shaft pinion in said bonnet, a crank gear driven thereby also in said bonnet, a plurality of pumping units in the same transverse plane of said crank gear and operated by said gear, and an up-standing bracing structure between said bonnet and the pumping units.

12. In an internal combustion engine marine power plant, the combination with the engine bed and superstructure, of a plurality of pumping units disposed in the same transverse plane of the engine and a single reciprocating member for operating them, said units being divided into groups and means for isolating one unit of the group from connection with the other.

13. In an internal combustion engine marine power plant, two or more pumping units mounted on the engine structure in the same transverse plane of said engine, said units being normally connected to pump in multiple relation in the same circulatory system, means for isolating any one of said units from said system and a cross head also disposed in said transverse plane of the engine and connected to both said pumping units.

14. In an internal combustion engine marine power plant, two or more pumping units mounted on the engine structure and in the same transverse engine plane, said units being normally connected to pump in multiple relation in the same circulatory system, an air chamber common to the deliveries of both said units, means for isolating either of said units from connection with said air chamber, and a cross head also disposed in the same transverse engine plane and connected to the plungers of both said pumping units.

15. In an internal combustion engine marine power plant, two or more pumping units mounted on the engine structure in the same transverse plane, said units being divided on opposite sides of the central vertical plane of the engine crank shaft and those units on one side being reverse dupli-

cates in structure of those on the other side and each unit having its valve chest disposed on the outer side of its structure with reference to the said vertical plane of the engine 5 crank shaft.

16. In a combustion engine power plant of the kind described, a plurality of pumping units all mounted on the engine structure and in the same transverse plane there-

on, said units having valve chests for their 10 respective inlet and outlet valves disposed on that side of the pumping cylinders which is opposite to the engine crank shaft, and having a single removable valve chest cover plate for both inlet and outlet valves. 15

In testimony whereof, I have signed this specification.

HUBERT C. VERHEY.
